UNITED STATES PATENT OFFICE.

THEODORE HUBERT, OF NEW YORK, N. Y., ASSIGNEE TO CHARLES F. SPLITDORF, OF NEW YORK, N. Y.

ELECTRIC IGNITION DEVICE.

No. 826,336.

Specification of Letters Patent. Patented June 22, 1908.

Application filed April 4, 1908, Serial No. 309,736.

To all whom it may concern:

Be it known that I, Theodore Hubert, a citizen of the United States, residing in New York city, borough of Manhattan, New York, have invented certain new and useful Improvements in Electric Ignition Devices, of which the following is a specification.

My invention relates to means for producing ignition or what is commonly called "jump sparks" particularly adapted for use in internal combustion engines, and the objects of my invention are to provide improved means for advancing or retarding the spark produced by a magneto.

To these and further ends my invention comprises the novel details of improvement and arrangement of parts that will be more fully hereinafter set forth and then pointed out in the claims.

Reference is to be had to the accompanying drawings forming part hereof, wherein

Fig. 1 is a central sectional view of a magneto embodying my improvements, Fig. 2 is a side view of the spark controlling device thereof, Fig. 3 is a cross section on the line 3, 3, in Fig. 2, Fig. 4 is a cross section on the line 4, 4, in Fig. 2, Fig. 5 is an end view looking from the right in Fig. 1, partly broken, Fig. 6 is a similar view looking from the left in Fig. 1, part being broken away and the protecting caps removed, Fig. 7 is a detail side view of part of the spark controlling device, Fig. 8 is an end view thereof looking from the right in Fig. 7, Fig. 9 is a detail view of part of the armature shaft, Fig. 10 is an end view of the connecting device between a driving shaft and the magneto shaft, Fig. 11 is a section of Fig. 10.

Similar numerals and letters of reference indicate corresponding parts in the several views.

The magneto 1, indicated in Figs. 1, 5, and 6 may, mainly, be of any well known construction provided with a distributor for distributing the secondary current to igniting devices or spark plugs. The armature 3 is mounted to rotate within usual fields, (not shown) and shaft 4 of the armature is rigidly attached thereto and mounted in suitable bearings carried by the magneto frame. The primary winding 5 of the armature is shown connected with a metal plate 6 rigidly carried by the armature but insulated therefrom, as by insulation 7, and

engaging a brush 8 carried by but insulated from the frame of the magneto.

At 9 is a contact in the primary circuit supported by and insulated from the frame of the magneto, and at 10 is a movable contact shown carried by a pivoted arm 10¹ supported by the frame of the magneto which may be grounded through the frame with which one terminal of the primary winding may also be grounded. The contact 10 is operated by a cam 11 carried by the magneto shaft 4¹, said cam being shown provided with two projecting portions to engage a roller 12 of arm 10¹, a coil spring 13 serving to pull the arm toward the cam, 76 whereby when the primary magneto circuit is closed and opened the discharge in the secondary armature winding 13 will be produced, in well known manner in high tension magneto. To control the magneto 75 primary circuit at will I provide a switch indicated at 14 in a branch line 15 (see Fig. 6). The secondary magneto winding 13 is shown connected by a screw 16, insulated from shaft 4¹, with a spring pressed 80 contact 17 in circuit with a binding post 18 shown carried by an insulating cap 19 screwed upon the magneto frame, the post 18 being shown connected (Fig. 1) by wire 20 with a post 21 in circuit with a distributor 85 contact 22, as by means of a spring pressed contact 23 shown carried by an insulating cap 24 attached to the magneto frame, the opposite terminal of the secondary winding 90 being grounded through the magneto frame.

The armature shaft 4 is shown provided with a bore 4¹ containing insulation 4² having a bore 4³, into which the inner end of post 18 projects but not in contact with insulation 4², whereby the latter may freely 95 rotate with respect to post 18. The screw 16 is secured into insulation 4² and the end of said screw projects into bore 4³ into engagement therewith with contact 17. Insulation 19¹ surrounding post 18 passes into bore 100 4³, but not in contact with insulation 4². At 16¹ is an insulating disk or plate over the inner end of shaft 4¹ and along the inner face of head 2¹ of the armature. By these means the secondary current is prevented 105 from leaking or jumping to the metal parts; as the insulation within the bore 4³ of shaft 1¹ provides too long a course through the bore 4³ for the current to reach the metal parts, outside of insulation 4², and the in- 110

sulation 16^a likewise insulates the adjacent parts of the armature from such current.

With the arrangements above described and the primary and secondary magneto circuits closed, current will be generated during the rotation of armature 3 as in well known high-tension magnetos, the discharges in the secondary circuit being produced during the make and break of the primary circuit at 10 the contacts 9, 10.

As it is desirable to advance, and retard the ignition or the sparking in internal combustion engines in accordance with the work required, I provide means for advancing 15 and retarding the armature 3 with respect to the armature driver or pistons of the engine so that the discharges in the secondary magneto circuit will be timed according to the requirements, and to this end I provide 20 the following arrangement:—Upon the magneto shaft 4 is loosely mounted a sleeve 26 that is provided with one or more projections or pins 26^a that enter spiral grooves 4^b in shaft 4, said projections being shown 25 extending from the bifurcated parts 26^b of sleeve 26, and upon sleeve 26 is mounted an arm 27 whose hub portion 27^a is so connected with sleeve 26 as to rotate with respect thereto and yet not have lateral motion 30 independent of said sleeve. I have shown ball bearings interposed between hub 27^a and sleeve 26, the sleeve 26 being shown provided with a ball-race 26^c receiving balls 28 within a cone or the like 29 carried by hub 35 27^a and shown held in place by a retainer 30 (see Figs. 1 and 3). Hub 27^a is shown provided with pins 31 that extend into slots 32 in blocks 33 secured on the magneto frame (see Figs. 2 and 3) which slots are disposed 40 at an angle to the plane of arm 27, said slots extending in opposite directions as indicated in Fig. 2, whereby as arm 27 is rocked in either direction around shaft 4 said arm and thereby sleeve 26 will be caused to move to 45 the right or left the desired distance along shaft 4 by reason of the ball bearings interposed between said sleeve and hub 27^a. This sliding motion of sleeve 26 on shaft 4 will, by reason of the projections 26^a of sleeve 26 50 entering grooves 4^b in shaft 4, cause said shaft to be rotated more or less and thus will adjust the armature correspondingly with respect to its fields and thereby with respect to the point of connection between shaft 4 and its driving part, such as an engine shaft, cam 11 being similarly adjusted with respect to contact 10. The blocks 33 are shown provided with interior concave faces 33^a (Fig. 3) providing a bearing for 55 hub 27^a which may rock therein, whereby said arm is held firmly and supported in addition to its support by the ball-bearings and thereby the arm 27 is kept from twisting, and side strain on the ball-bearings is 60 reduced, thereby also lessening friction in 65

the bearings and serving to take the thrust when arm 27 is rocked.

Connection is to be made between the driving part or an engine shaft and sleeve 26 so that shaft 4 of the armature will be 70 free for adjustment with respect to the engine shaft and yet be rotated thereby, and to this end I have shown a sleeve or driving part 35 mounted freely upon shaft 4 and provided with internal grooves 35^a that receive the arms or projecting portions 26^b of sleeve 26, in the nature of a tongue and groove connection, whereby sleeve 26 may slide along shaft 4 freely with respect to sleeve 35 and maintain rotary connection 80 therewith. A convenient means for providing the grooves 35^a in sleeve 35 is to insert within sleeve 35 a sleeve 36 (see Figs. 1 and 11) that is provided with slots 35^a, and to secure said sleeves together by pins 37. The 85 sleeve 35 is to be rigidly connected with a driver, as with a shaft of a gas engine, whereby the rotation of said shaft will be communicated to the armature 3. It will be understood that a single groove 4^b, projection 26^a, arm 26^b, groove 35^a, pin 31 and slot 32 may be used if preferred, or that other suitable means for a sliding and rotative connection between sleeves 26 and 35 may be provided, and also that other means may 90 be provided than the ball-bearings above described between sleeve 26 and hub 27^a for providing rotative yet positive connection therebetween for causing the rotary and lateral motion of hub 27^a to rotatively 95 adjust shaft 4 and armature 3.

From the foregoing it will be understood that with an engine shaft connected with sleeve 35, to thereby have rotary connection with shaft 4, and with arm 27 in position to 105 cause retarded breaks in the secondary circuit of the magneto, that the explosions in the engine cylinders, whose igniters are to be connected with the distributor contacts 22^a, 22^b, 22^c, 22^d in well known manner, 110 will be "late" owing to the fact that with respect to the position of the corresponding piston the break in the primary magneto circuit will be retarded. To advance the spark in the engine cylinder the arm 27 will be 115 rotated a suitable distance to cause its pins 31 to travel through slots 32, (in the position represented in Fig. 3), whereby sleeve 26 will be moved to the right (in Fig. 1) and its projections 26^b, acting with grooves 120 4^b of shaft 4, will rotate said shaft forwardly independently of sleeve 35, and thus independently with respect to the driving shaft, thereby also advancing cam 11 with respect to contact 10, whereby the break in 125 the primary magneto circuit will be caused to occur earlier than before, and so on, according to the limit of rotation of arm 27, the armature and cam being thereby correspondingly advanced with respect to the en- 130

gine shaft and the piston. To retard the "spark," arm 27 is moved reversely, the pins 31 and slots 32 causing sleeve 26 to move to the left in Fig. 1, thereby correspondingly rotating shaft 4 and armature 3 reversely with respect to sleeve 35 and the engine shaft, and thus retarding the breaking of the primary magneto circuit with respect to the engine shaft and pistons.

10 The distribution of the secondary current for a plurality of spark plugs of the engine cylinders is produced by the contact 22 whose shaft 49 is geared to the shaft of the armature, as in the ratio of two to one for a four cylinder engine, by means of gears 41 and 42 carried by said shafts respectively, as shown in Fig. 1, and thereby it will be understood that as shaft 4 and its armature 3 are advanced or retarded with respect to the driving part or engine shaft the distributor contact 22, through said gearing, will be correspondingly advanced or retarded to cause the distribution of the secondary current for the several cylinders of the engine to accord in time and position with the breaking of the primary circuit of the magneto, the contact 22 controlling contacts 22^a, 22^b, 22^c and 22^d, to be connected by wires *a'* with the spark plugs. The shaft 40 carries an insulating stem 55 into which the shaft projects and which may be secured thereto by a pin 56, and stem 55 carries a threaded plug or screw 57 which may be secured to said stem by a pin 58, which plug or screw carries the contact 22 that may be held firmly thereon by nut 59. The stem 55 rotates freely within a bore 60 in an insulating block 61 secured on the magneto frame. The contacts 22^a, 22^b, 22^c, 22^d, pass through and are supported by the insulating block 61, are insulated from the magneto frame by insulation 62, and are connected respectively with wires *a'*. The wires *a'* extend through suitable holes, as at 45 63, in the magneto frame, and their bared ends *a'* project into transverse holes 64^b in metal plugs 64, and the screws 65 entering said plugs engage the ends *a'* of the wires and hold them firmly to said plugs. The 50 plugs 64 are located in pockets or bores 66 in the insulating block 67 secured on the magneto frame, and the bared ends *a'* of the line wires *a* enter bores 64^b in plugs 64, (see Figs. 1 and 6). The wires *a* may be 55 firmly held upon the magneto frame by insulating blocks 68 having bores 68^a receiving said wires, and blocks 68 may be secured on block 67 by screws 69. With the arrangements described the contact 22 is 60 firmly supported by shaft 40 and insulated therefrom and from the magneto frame. By having the plugs 64 located within the bores of the insulating blocks 67 and the connection of the wires *a* and *a'* with said blocks made within said bores, the connec-

tions of said wires are protected to prevent the escape of secondary current and the several wires and plugs are insulated from each other and from the magneto frame, and this arrangement permits ready connection of 70 the wires with plugs 64 when desired.

My improvements above described may be used in an ignition system of internal combustion engines, as in automobiles, boats, and the like, either independently of a battery circuit or in connection therewith. To this end I have shown the wire 15 of the primary magneto circuit connected with a binding post *b* and the wire 15^a of said circuit connected with a binding post *c*, wires 80 15^b, 15^c connecting said posts *b* and *c*, respectively, with a suitable contact and a switch. I have shown a contact *d* connected with wire 15^b and a switch 14 connected with wire 15^c and such circuit is adapted 85 to be opened and closed by the contact or switch 14, the primary circuit then being from brush 8, through switch 14 and said wires, contacts 9, 10 and through the primary coil back to brush 8.

When a battery and vibrator coil are used in connection with the magneto the wire *a* from the vibrator primary coil may lead to post *p*, and wire *q* to a spring or contact *q* adapted to make and break circuit with 95 movable member 10^a, which member leads thence back to the battery as by ground through the mechanism. The contacts *b*, *c*, and *p* are shown carried by an insulating piece 50, such as rubber, that may be held upon the magneto frame by screws 51. (See Fig. 6). The rotation of cam 11 will cause the primary battery circuit to be made and broken at contacts 10 and 48.

It will be understood that the magneto circuits may be used independently of battery circuits, and that when so used a switch such as 14, may be used with wires as 15, 15^a, switch 14 and contact *d*, as indicated in Fig. 6, for at will controlling the primary magneto circuit.

My invention is not limited to the details of construction and arrangements of parts shown and described as they may be varied without departing from the spirit thereof.

Having now described my invention what I claim is:—

1. The combination of a magneto, with an arm mounted concentrically with respect to the armature axis, means to cause said arm to move bodily laterally as it rocks, and means connecting said arm with said armature for causing rotary movement of said armature by the lateral movement of said arm while permitting said armature to rotate independently of said arm.

2. The combination of a magneto, with an arm mounted to rock transversely of the armature axis, means to cause said arm to

move in the direction of said axis, a sliding part connected with said arm, and means to convert the sliding movement of said part into rotary adjustment of the magneto armature.

3. The combination of a magneto, with an arm mounted concentrically with respect to the axis of a magneto armature, a stationary part, means connecting the latter with said arm for causing the arm to move laterally when rocked on its axis, a sliding part connected with said arm, and means for converting the sliding movement of said part into rotary adjustment of the armature with respect to its driving part.

4. The combination of a magneto, with a driving part to rotate the armature shaft, an arm, a stationary part, means connecting the latter with said arm for causing the arm to move laterally when rocked on its axis, a sleeve to slidably connect said arm with said driving part, and means to rotatively connect said sleeve with the armature shaft to cause rotary adjustment of said shaft with respect to said driving part by the sliding movement of said sleeve.

5. The combination of a magneto, with a rock arm, mounted concentrically of the axis of said armature, means to shift said arm bodily laterally as it rocks, a sleeve connected with said arm, and means connecting said sleeve with the armature shaft to cause rotary adjustment of the armature during the rotary adjustment of said arm.

35 6. The combination of a magneto, with a rock arm, mounted concentrically of the axis of said armature, means to cause said arm to move bodily laterally during its rocking movements, a sleeve rotatively connected with said arm to be moved parallel with the armature shaft by said arm, a driving part having sliding connection with said sleeve, and means interposed between the sleeve and the armature shaft for causing rotary adjustment of the latter with respect to the driving part.

7. The combination of a magneto having a shaft to operate its armature, with a sleeve mounted upon said shaft, an arm rotatively mounted upon the sleeve and having connection therewith to slide the sleeve along the shaft, means to move said arm laterally during its rotary movements, a tongue and groove connection between the sleeve and shaft for adjusting the latter rotatively by the sliding movement of the sleeve, and a driving part having sliding connection with said sleeve.

8. The combination of a magneto having a shaft for operating its armature, with a sleeve mounted upon said shaft, an arm rotatively mounted upon said sleeve and having connection therewith to move the sleeve along the shaft, said sleeve having a projec-

tion and said shaft having a spiral groove 65 receiving said projection, a driving part, and a sliding connection between said sleeve and driving part.

9. The combination of a magneto provided with a shaft for operating its armature, with a sleeve upon the shaft, an arm rotatively mounted upon the sleeve and connected therewith to move the sleeve along the shaft, a stationary slotted part, a projection from said arm entering said slot, a 75 spiral groove and tongue connection between the sleeve and shaft, a driving part, and means for slidably connecting said sleeve and driving part.

10. The combination of a magneto provided with a shaft for rotating its armature, with a sleeve mounted upon the shaft, an arm rotatively mounted upon the sleeve, anti-friction bearings between the sleeve and the arm, means to adjust the arm laterally during its rotation to slide the sleeve along the shaft, a spiral groove and tongue connection between the sleeve and shaft, and means for rotating said sleeve.

11. The combination of a magneto having 90 a shaft to operate its armature, with a sleeve mounted upon said shaft, an arm rotatively mounted upon the sleeve, means to cause the arm to have lateral movement to slide the sleeve along the shaft, a tongue and spiral 95 groove connection between the shaft and sleeve, and a driving part freely mounted upon the shaft and slidably connected with said sleeve.

12. The combination of a magneto having 100 a shaft to operate its armature, with a sleeve mounted upon said shaft and rotatively and slidably connected with said shaft to adjust the same within the sleeve, an arm rotatively mounted upon said sleeve to move the latter, 105 said arm having a hub provided with a projection, a stationary block having a slot receiving said projection, and a driving part freely mounted upon said shaft and having a sliding connection with said sleeve.

13. The combination of a magneto provided with a shaft for its armature, with a sleeve upon the shaft, an arm upon the sleeve, ball-bearings interposed between said arm and sleeve arranged to move the latter along 115 the shaft by the lateral movement of said arm, means to cause said sleeve to adjust the armature with respect to a driver, and means to cause said arm to move laterally when rocked.

14. The combination of a magneto provided with a shaft for its armature, with a sleeve upon the shaft, an arm upon the sleeve, ball-bearings interposed between said arm and sleeve arranged to move the latter along 125 the shaft by the lateral movement of said arm, means to cause said sleeve to adjust the armature with respect to a driver, a station-

ary part, and means connecting said part with said arm for moving the arm laterally when rocked.

15. The combination of a magneto provided with a shaft for its armature, with a sleeve upon the shaft, an arm upon the sleeve, ball-bearings interposed between said arm and sleeve arranged to move the latter along the shaft by the lateral movement of 10 said arm, means to cause said sleeve to adjust the armature with respect to a driver, a stationary part, and a pin and slot connection between said part and said arm for causing the latter to move laterally when 15 rocked.

16. The combination of a magneto provided with a shaft for its armature, with a sleeve upon the shaft, an arm upon the sleeve, ball-bearings interposed between said 20 arm and sleeve arranged to move the latter along the shaft by the lateral movement of said arm, means to cause said sleeve to adjust the armature with respect to a driver, a stationary part provided with a slot 25 extending at an angle to the plane of said arm, and a projection from said arm entering said slot to cause the arm to move laterally when rocked.

17. The combination of a magneto provided with a shaft for its armature, with a sleeve upon the shaft, an arm upon the sleeve, means rotatively connecting said sleeve and arm to move one by the other, said arm having a hub, a bearing receiving 35 said hub, and means for causing said arm to move laterally when rocked.

18. The combination of a magneto provided with a shaft for its armature, with a sleeve upon said shaft, an arm upon the 40 sleeve, ball-bearings interposed between said arm and sleeve arranged to move the latter along the shaft by the lateral movement of said arm, means to cause said sleeve to adjust the armature with respect to a 45 driver, said arm having a hub, a bearing receiving said hub, and a pin and slot connection between said hub and bearing for causing said arm to move laterally when rocked.

50 19. The combination of a magneto having an armature provided with a shaft having a bore, insulation within said bore provided with a bore, a contact carried by said insulation and connected with the armature secondary 55 winding, a contact within the bore of said insulation in circuit with the first named contact, and insulating means supporting said second named contact.

20. The combination of a magneto having

an armature provided with a shaft having a bore, insulation within said bore provided with a bore, a contact carried by said insulation and connected with the armature secondary winding, a contact within the bore of 60 said insulation in circuit with the first named contact, insulating means supporting said second named contact, a distributor having a movable contact, and a conductor connecting said movable contact with said second named contact. 70

21. The combination of a magneto having an armature provided with a shaft having a bore, insulation within said bore provided with a bore, a contact carried by said insulation and connected with the armature secondary 75 winding, a stationary contact within the bore of said insulation and out of engagement therewith, and an insulating support for said contact.

22. The combination of a magneto having an armature provided with a shaft having a bore, insulation within said bore provided with a bore, a contact carried by said insulation and connected with the armature secondary 80 winding, a stationary contact within the bore of said insulation and out of engagement therewith, and an insulating support for said contact provided with insulation around said stationary contact and extending into the bore in the first named 85 insulation.

23. In a magneto, the combination of an armature having primary and secondary windings, a secondary shaft driven with said armature and carrying a contact, stationary 90 contacts to be engaged thereby, an insulating block provided with bores, metal plugs in said bores, wires connecting said plugs with said stationary contacts and attached to said plugs within the bores of said insulating 95 block, and conductors connected with said plugs within said bores. 100

24. In a magneto, the combination of an armature having primary and secondary windings, a secondary shaft driven with 105 said armature and carrying a contact, stationary contacts to be engaged thereby, an insulating block provided with bores, metal plugs in said bores, wires connecting said plugs with said stationary contacts and attached to said plugs within the bores of said blocks, said plugs having bores 64^b and conductors having bared ends secured in the bores 64^b of said plugs. 110
